ABSTRACT OF THE DISCLOSURE

A valve including an inlet duct 10 with an opening 12 closable by a valve plate 19 which is moved between a solid line open position and a dotted line closed position by a piston rod 22 as shown in FIGURE 2. For positively controlling the pivotal angle of the plate to a predetermined angle in all locations between the open and closed position, rollers 27 and 28 traverse along a pair of rails 25 and 26 preventing flopping movement of the plate and insuring positive angle control.

The present invention relates to improvements in pressure charging devices and more particularly to an improved control for charging material such as wood chips into a pressurized tank through a control inlet to the tank.

In continuously processing compactible material such as wood chips, straw, bagasse, cotton linters and other cellulosic materials, it is necessary to feed the materials through a duct communicating with the tank. The materials are compacted to a density sufficient to prevent loss of pressure in the tank as they are charged. Because of the difficulty of determining when adequate density is attained it is customary to compact the material more than necessary to maintain the seal. Charging must occur intermittently and the compacted material must be broken up as it passes through the charging unit. It is essential that the charging unit maintain a seal during times of intermittent feeding and that it functions to permit such intermittent feeding, sealing when feeding does not occur, and breaking up the material during charging.

It is accordingly an object of the present invention to provide an improvement in charging devices for pressure feeding material such as wood chips into a pressure tank.

Another object of the invention is to provide an improved structure for a valve plate for a charging device wherein the valve plate is positively controlled and positioned for breaking up the material and insuring that the valve will return to sealing position when it is closed.

A more specific object of the invention is to provide an improved valve position control mechanism for a charging device of the type disclosed in U.S. Patent 2,954,883.

Other objects, advantages and features will become more apparent in connection with the teaching of the principles of the present invention in the disclosure of the preferred embodiments thereof in the specification, claims and drawings in which:

FIGURE 1 is a top plan view with a portion broken away to show the valve mechanism; and

FIGURE 2 is a vertical sectional view taken substantially along line II—II of FIGURE 1.

On the drawings:

As shown in FIGURES 1 and 2 the charging device includes a duct 10 through which the materials are delivered and compacted. While it will be understood that the device is capable of operating in various environments providing the advantages of the invention, for convenience of description it will be described in connection with a charging mechanism for charging wood chips into a pressure cooker mechanism.

The chips are compacted by a screw feeder 11 which densifies or compacts the chips sufficiently to prevent the

2

escape of pressure through the duct 10 from the delivery passage 13 which leads downwardly to the pressure cooker. The duct 10 leads through a horizontal opening 12 and the delivery passage 13 leads downwardly at an angle transverse, or in other words at right angles to the opening 12.

The delivery duct 13 is provided in a housing 18 having a cleanout opening 17 at the upper end. The cleanout opening is closed by cleanout plate 14 held in place by bolts 15 which are threaded into a housing flange 16.

For controlling passage of the compacted chips through the opening 12, for sealing the opening 12, and for breaking up the compacted material, a material deflecting valve plate 19 is provided.

The valve plate is pivotally supported on a support pin 21 passing through flanges 20 on the back of the plate and mounting it on a piston rod 22. The piston rod passes through a seal 23 and the piston 22a is slidably received in a cylinder 24 which connects to a pressure control line, not shown.

The deflecting valve plate 19 is movable from a closed sealing position (as shown at the dotted line position of FIGURE 2) to an open position (as shown at the solid line position in FIGURE 2). In movement between the closed and open positions, in accordance with the principles of the present invention, the angular position or attitude of the valve plate 19 is positively controlled. This control positions the plate in a predetermined positive position, and also prevents sudden surges or fluctuations, or changes in force on the plate due to the compacted material, from tipping the valve plate to a non-operational position. Such tipping of the plate which might be caused by sudden expansion of a plug of material coming through the opening, when accompanied by a sudden closing of the valve might jam the valve plate in a nonoperational position and damage it, or destroy the seal so as to prevent further functioning of the charging mechanism.

For controlling the position of the valve plate it is pivotally supported below its center so that thereby forces from the material passing through the opening 12 will normally act above the pivotal support point, and so that gravity will tend to tip the plate downwardly.

For controlling the position of the valve plate and preventing it from tipping over backward (which would occur if the upper end could move freely to the right, as shown in FIGURE 2), a pair of guide rails 25 and 26 are positioned along the sides of the plate. These guide rails are bolted to supports 33 and 34 in the housing 18 by bolts 31 and 32. The guide rails 25 and 26 are parallel to each other and are positioned at a predetermined angle so as to control the angle of the valve plate 19.

At the upper edge 30 of the valve plate are rollers 27 and 28 mounted on brackets 29 and 30 on the valve plate. The rollers are rolled down the downwardly facing edges of the guide rails 25 and 26 in the manner illustrated in FIGURE 2.

In operation during starting the valve plate is held in the closed dotted line position shown in FIGURE 2 until the screw feeder 11 compacts sufficient material to prevent the escape of pressure. The valve plate 19 is then withdrawn a predetermined distance by the piston rod 22 as the compacted material is delivered through the opening 12 and engages the valve plate 19 to be broken up as it drops downwardly through the delivery passage 13. Normally the compacted material will continually engage the valve plate to be deflected downwardly, but should the valve plate be free of engagement of material, it would be prevented from tipping completely downwardly by the heel 20a of the brackets 20 engaging the shoulder 21a at the base of the slot of the piston rod.

When the density of the material delivered by the screw

conveyor 11 becomes less, the pressure on the piston rod automatically tends to move the plate to closed position. In other words there normally is a continual pressure on the piston rod 22 to the left so that the opening 12 will automatically become closed if the density of the material fed through the opening diminishes, and the valve plate 12 will be forced toward open position as the density increases, thereby maintaining a self-sealing charging mechanism. In all positions of the valve plate it will be held in the desired attitude to obtain optimum dispersion or breaking of the compacted delivered material.

Thus it will be seen that I have provided an improved charging device and particularly a valve control apparatus which meets the objectives and advantages above set forth. The mechanism is capable of continued reliable operation without adjustment or attention and is so constructed as to avoid jamming or clogging due to the material being delivered.

I claim as my invention:

1. In a charging device having force means for compacting and feeding material axially through a charging opening:

a delivery passage extending downwardly laterally of the opening,
a material deflecting valve plate moving through a path from a closed position wherein the plate sealingly engages the opening, to an open position wherein the plate is spaced axially away from the opening,
said plate being pivotally supported below its center for movement about an axis transverse of the opening and transverse of the delivery passage with said plate deflecting material from the opening laterally into the delivery passage in all positions of the plate spaced from the opening,

the improvement comprising means positively controlling the pivotal angle of the plate to a predetermined angle in all positions of the valve plate so that the plate will remain accurately inclined relative to the axis of the opening as it is moved from closed to open position.

2. In a charging device constructed in accordance with

claim 1 wherein said angle controlling means is connected to the upper free edge of said plate for applying a force thereto transverse of the pivotal axis of the plate.

3. In a charging device constructed in accordance with claim 1 wherein said angle controlling means includes an angular guide member extending at an angle to the path of movement of the pivotal support of the plate and includes a member on the plate engaging said guide member and positioning the plate.

4. In a charging device constructed in accordance with claim 1 wherein said angle controlling means includes an angular rail extending at an angle to the path of movement of the pivotal support of the plate and includes a sliding member attached to the plate slidably engaging said angular rail.

5. In a charging device constructed in accordance with claim 1 and including an angular rail extending at an angle to the path of movement of the pivotal support of the plate and including a roller on the upper edge of the plate engaging the rail and traversing therealong as the plate is moved between open and closed positions.

6. In a charging device constructed in accordance with claim 1 wherein said angle controlling means includes a pair of rails mounted at each side of the plate and further includes a roller at each side of the plate engaging the rails and moving therealong as the plate is moved between open and closed position.
